UNITED STATES PATENT OFFICE.

MORRIS B. HALL, OF ESSEX, CONNECTICUT.

WINDOW-HOIST.

SPECIFICATION forming part of Letters Patent No. 351,976, dated November 2, 1886.

Application filed April 12, 1886. Serial No. 198,534. (No model.)

To all whom it may concern:

Be it known that I, MORRIS B. HALL, of Essex, in the county of Middlesex and State of Connecticut, have invented a certain new and useful Improvement Pertaining to Window-Hoists, of which the following is a description, reference being had to the accompanying drawings, where—

Figure 1 is a front view of my device attached to a window, with the swing buttoned back to the tackle-frame. Fig. 2 is a central vertical section of the same device which is shown in Fig. 1, with the swing let forward and the landing-plate in place.

One main object of the improvement herein shown and described is to aid in hoisting from the ground to the window of any of the upper stories of a building any heavy object, like a piano or safe, and the convenient conveyance of the same through the window and into the building.

The letter *a* denotes what may appropriately be termed a "tackle-frame," intended to be temporarily attached to a window, for the purpose hereinbefore specified.

The letter *b* denotes a ledge-support projecting from the side of the lower part of the tackle-frame, and intended to rest upon the lower part of the window, commonly called a "window-ledge."

The letter *c* denotes what may be termed the "upper support" of the tackle-frame. It is pivoted to the tackle frame so that its opposite end may be vertically adjustable for the purpose of attaching the tackle-frame to windows of different heights.

The letter *d* denotes clamp-hooks to be temporarily affixed to the top of the window-opening, for which purpose they are provided with set-screws *d'*, and also provided with hooks *d''*, to take temporary hold of the upper support, *c*.

The letter *e* denotes the tackle as a whole, by which the heavy object is to be raised from the ground up to a point above the bottom of the window.

The letter *f* denotes what I will term a "swing," pivotally attached to the tackle-frame, and buttoned back to the tackle-frame while the weight is being raised, as illustrated in Fig. 1. After the weight is up this swing is swung forward or outward, as shown in Fig. 2, when it will be beneath the heavy object which has just been raised. A landing-plank, *g*, is then laid from the window-ledge into the swing and the heavy object is deposited thereon. The heavy burden and the landing-plank are swung inward till the burden rests upon the window-ledge, when the landing-plank is carefully tipped until its inner end rests upon the floor, when the burden can be easily moved downward upon it and upon the floor of the room.

The landing-plank is or may be provided with raised edges or low walls, to prevent the burden from accidentally getting sidewise off the landing-plank.

I claim as my improvement—

1. In combination, the swing, the tackle-frame, and supports for attaching the tackle-frame to a window, all substantially as described, and for the purpose set forth.

2. In combination, the swing, the tackle-frame, the ledge-support, the upper support pivoted to the tackle-frame, and the clamp-hooks for the upper part of the window, all substantially as described, and for the purpose set forth.

MORRIS B. HALL.
